UNITED STATES PATENT OFFICE.

WAYNE LESLIE CARTER AND DELOS BUTTLES STULTS, OF WAVERLY, ILLINOIS.

CULTIVATOR.

1,112,889.

Specification of Letters Patent.

Patented Oct. 6, 1914.

Application filed January 22, 1913, Serial No. 743,559. Renewed April 24, 1914. Serial No. 834,222.

To all whom it may concern:

Be it known that we, WAYNE L. CARTER and DELOS B. STULTS, citizens of the United States, residing at Waverly, in the county 5 of Morgan, State of Illinois, have invented certain new and useful Improvements in Cultivators; and we do hereby declare the following to be a full, clear, and exact description of the invention, such as will enable others skilled in the art to which it 10 appertains to make and use the same.

This invention relates to cultivators and more particularly to means for adjusting the shovel thereof.

15 The invention has for its object to construct a device of this character in such a manner that the shovel may be adjusted vertically and angularly.

With these and other objects in view, this 20 invention resides in the novel features of construction, formation, combinations and arrangements of parts to be hereinafter more fully described, claimed and illustrated in the accompanying drawing, in which:

Figure 1 is a front view of the device. Fig. 2 is a rear view. Fig. 3 is a sectional view on line 3—3 of Fig. 2. Fig. 4 is a similar view on line 4—4 of Fig. 2.

30 Referring to the drawing, the numeral 1 designates a cultivator shovel of any well known shape, and to the rear face of which is secured a sleeve 2, said sleeve being provided with internal threads 3. Formed 35 upon the rear surface of the sleeve 2 is a pair of spaced ears 4 and between which is pivotally mounted a lever 5, the inner end of which is formed with a curved head 6. The head 6 is adapted for operation in the 40 vertical slot 7 formed in the rear surface of the sleeve 2 and between said ears.

The standard 8 is circular in cross section for its major length and is provided with threads 9 so that the threads 3 of the sleeve 45 2 may engage therewith. The rear surface of the shank 8 is provided with a plurality of spaced longitudinal grooves 10, either one of which being adapted to register with the

slot 7 in the sleeve 2 so that the curved portion 6 of the lever 5 will engage therewith 50 to hold the shovel in different angular adjustments.

From the foregoing description it will be seen that when it is necessary to vertically adjust the shovel 1 it is only necessary to 55 operate the lever to disengage one of the slots 10 whereupon the sleeve may be rotated to raise or lower the shovel, as the occasion may require. Further it will be noted that when it is desired to angularly 60 adjust the shovel it is only necessary to rotate the sleeve until the slot 7 therein registers with the desired groove, whereupon the lever 5 is swung downwardly at which time the curved portion 6 engages the proper 65 groove and holds the shovel properly adjusted as well as against accidental rotation.

What is claimed is:

1. In combination with a cultivator shovel standard having threads formed thereon, of a shovel having an interiorly threaded sleeve fixed thereto and adapted to engage the threads of the standard, a plurality of longitudinal grooves formed in the shank, a lever carried by the sleeve for engaging in one 75 of the grooves, as and for the purpose set forth.

2. In combination with a cultivator shovel standard having threads formed thereon, of a shovel having an interiorly threaded 80 sleeve mounted thereon and adapted to engage the threaded standard, ears formed upon the sleeve, said sleeve having a slot formed therein and located between the ears, a lever pivotally connected between the ears, 85 a plurality of longitudinal slots formed in the standard, any one of which may be engaged by the lever to hold the shovel in different adjusted positions upon the standard.

In testimony whereof, we affix our signatures in the presence of two witnesses.

WAYNE LESLIE CARTER.
DELOS BUTTLES STULTS.
